UNITED STATES PATENT OFFICE

GEORGE W. RUSSELL, OF STOCKTON, CALIFORNIA

AUTO SCREEN ATTACHMENT

Application filed March 13, 1928. Serial No. 261,394.

This invention relates to accessories for automobiles and particularly automobiles of that type known generally as closed cars.

The principal object of my invention is to provide a screen attachment which is adapted to be applied to any or all the windows of such cars, so arranged that flies, gnats, and other insects are prevented from entering the car when the windows are open. At the same time the screens are adjustable so as to provide an unobstructed opening when necessary, as when desiring to give arm signals, etc. By means of this attachment, therefore, the occupants of the car can have the necessary ventilation and fresh air, without the possibility of being inconvenienced and bitten by insects of various kinds, which at certain seasons are very numerous and are apt to enter the car through an open window in considerable numbers.

A further object of the invention is to construct the screen device so that it may be easily and removably mounted on the vehicle in but a few seconds' time, without the use of screws or other more or less permanent connection means, and also without marring the finish or mutilating the window frames of the car in any manner.

The attachment is also mounted on the window frames in such a manner as to offer no interference with the free opening and closing of the windows themselves.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a fragmentary perspective outline of the interior of a motor vehicle showing my screen attachment applied to the front door windows.

Fig. 2 is an enlarged vertical cross sec-

tion through the screens and their supporting members, as mounted on the door.

Fig. 3 is a sectional plan of the door frame, showing the lower screen-frame support mounted thereon, with the screen- 55 frames removed.

Fig. 4 is a similar view showing the screen-frames in place on the support.

Fig. 5 is a fragmentary perspective view of the lower screen-frame supporting bar 60 unit.

Referring now more particularly to the characters of reference on the drawings, the numerals 1 and 2 denote the vertical and horizontal frame members respectively surrounding the window opening of the car door 3, said window frame being a portion of the actual door structure itself as is the case in structures of this kind. The window pane 4 is slidable vertically in guide channels 5 which are mounted in the side frames 2 intermediate their inner and outer edges. These parts are standard in one form or another in various makes of cars and I do not change the arrangement in any way. 75

My attachment comprises horizontal bar units 6 to extend substantially the full distance between the frames 1 inwardly of the pane, at the top and bottom of the frame. The faces of these bars nearest the horizontal window frame members are shaped to conform to the transverse shape or slope of said frame members as shown, and are edged with felt 7 or the like. The adjacent faces of these bar units have longitudinal and transversely spaced grooves 8 therein, which are also preferably lined with felt. Slidably mounted in these grooves are the screen-frames 9 which are arranged in close transversely spaced relation and covered with suitable metal screening 10. The adjacent vertical ends of the screen-frames, where they overlap, are made quite narrow as shown at 11, so as not to materially interfere with the vision at that point. One or both screen-frames may be provided with handles 12 so that they can be slid one way or the other. I have here shown both screens as being shiftable 90

95

100

but one or the other may be made stationary if desired.

To hold the guide bars 6 against unintentional displacement they are provided at their ends with rigid metal pads 13 to engage the adjacent faces of the window frames, the pads being faced with heavy felt. These pads are shaped so as to engage the grooves found between the window frame and the window-guide channels, as at 14 and extend to the inner edge of the frames, so as to prevent positive lateral displacement of the bars with any slamming movement of the door. One of the pads is disposed directly against the corresponding end of the bar, while the other is mounted on a stem 15 which is slidable in the adjacent end of the bar and is pressed outwardly against the window frame by a spring 16. The space between the bars and the window frame, at the end on which the spring pressed pads are mounted is covered by a short strip of felt or the like 17 which is secured to the bars, so as to prevent the passage of insects through said space, while offering no interference with the lengthwise movement of the bar necessary when attaching or removing the same.

In order to enable the length of the bars to be initially adjusted to conform properly to the length of the window at which they are to be applied, without depending on the movement of the stem 15 and the spring 16 to take up such difference, I preferably make each bar unit of two pieces rigidly connected together by metal straps 18 on the sides. These straps are permanently secured to one piece, and are initially adjustable, when the attachment is being installed, relative to the other piece. When such installation is being made the unit is fitted in place with the desired amount of spring tension, and the plates are then permanently connected to said other bar piece by screws 19 or the like. This enables short variations in the length of the bars to be had, so as to enable one attachment to fit various cars of different makes and sizes but of approximately the same window dimensions.

The screen-frames also are made to overlap at their adjacent ends a distance equal at least to the possible separation of the bars, so as to enable the bars to be adjusted as to length while using the same pair of screen-frames for all such adjustments.

When it is desired to remove the attachment, it is only necessary to press the bars horizontally to compress the springs 16 so that the rigid pads on the other ends of the bars are disengaged from the window frame and can be shifted inwardly of said frame with said bars. The spring-pressed pads can then be drawn clear of engagement with the window frame, and the entire attachment thus removed as a unit, as will be evident.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a screen attachment for closed car windows, a bar to support one edge of a screen frame, pads on the ends of the bars to engage the side frames of the window inwardly of the window pane, and spring means acting to force the pads apart whereby they will frictionally engage the frames.

2. A structure as in claim 1, with flexible strips secured to the outside of the bar at the ends thereof to project across the space between the ends of the bar and the adjacent side frames and overlap the latter.

3. In a screen attachment for a closed car window, a bar grooved along one edge to receive and support one edge of a screen frame, and yieldable means projecting from the ends of the bar to frictionally engage the side edges of the window frame to hold the bar in place and prevent lateral movement thereof relative to the frame.

4. In a screen attachment for a closed car window, a bar grooved along one edge to receive and support one edge of a screen frame, pads disposed beyond the ends of the bar shaped to engage the side frames of the window, stems provided with the pads and slidable in the ends of the bar, and springs to force the pads outwardly relative to the ends of the bar.

5. Supporting means for screen-frames, comprising a pair of separate longitudinally aligned bars, transversely spaced matching grooves along the bars to slidably receive the frames, relatively thin side-straps on the bars securing the adjacent ends of the same together, and means mounted in connection with the bars for holding them in place in a window-frame.

In testimony whereof I affix my signature.

GEORGE W. RUSSELL.
